UNITED STATES PATENT OFFICE.

LEE H. PAYNE, OF CHICAGO, ILLINOIS.

BOTTOM FOR BOTTLE-CRATES.

1,385,709.

Specification of Letters Patent. Patented July 26, 1921.

Application filed January 31, 1921. Serial No. 441,138.

To all whom it may concern:

Be it known that I, LEE H. PAYNE, a citizen of the United States, residing at Chicago, in the county of Cook and State of Illinois, have invented certain new and useful Improvements in Bottoms for Bottle-crates, of which the following is a specification.

This invention relates to bottle crates, for instance crates composed of pairs of opposed confining walls with intersecting partitions subdividing the interior space of the crate into compartments to receive bottles and to hold them out of contact with one another to avoid breakage; and the invention relates particularly to the construction of the bottom for such a crate affording support for the bottles introduced into the compartments.

The object of the invention is to provide a bottom construction which will be very cheap and durable and very quickly assembled from easily obtainable stock materials, but which will be adapted, when completed, to support the bottles well above the ground or other contacting surface, will have a measure of inherent elasticity that will effectively insure the bottles against breakage even though carelessly dropped into the pockets, and will retain its form and structure in spite of rough usage and thus avoid possibility of the bottles dropping through on to hard surfaces, even though the bottles be inserted in inverted position as is frequently done, particularly when they are being drained after washing.

The invention proceeds upon the principle of utilizing for the load bearing members of the bottom relatively thin flat strips of metal with inherent flexibility and, preferably, resiliency, extended between and anchored to opposed walls of the crate, with their flat faces and lesser transverse dimension presented in the direction to receive the load of the inserted bottles so that the strips develop a high degree of flexibility and absorb the shock of bottles dropped into the pockets; and, in order to insure the proper spacing intermediately of the anchored ends of these load-bearing strips and to prevent them from sagging down under the load of bottles and to accomplish this without interfering with their flexibility, providing an intermediate transverse sustaining bridge also constructed of a flat metal strip and extended between and anchored to the opposed

walls of a pair, but in position to intersect the load-bearing strips first named; this bridging strip being constructed with slots extending therethrough in line with and conforming substantially to the section of the load-bearing strips, and having the latter threaded through these slots so that they are confined against both vertical and lateral displacement but not against longitudinal movement or rocking movement incident to the flexing or resilient action of the supporting strips, and thereby permitting each strip to flex upwardly on one side of the bridge in response to a depression of said strip on the other side of the bridge. Preferably the anchoring ends of the bridging strip are deflected to bring their lesser dimension in the direction of the load while leaving the bridging strip with its greater dimension vertical throughout the greater portion of its length, thus not only facilitating the anchoring of the ends of the bridging strip, but obtaining an additional measure of resiliency in the bottom.

The invention will be fully understood upon reference to the accompanying drawing, in which—

Figure 1 is a perspective view of a crate having the subject-matter of the present invention embodied therein.

Figs. 2 and 3 are, respectively, a vertical longitudinal section and a vertical transverse section of the same; and

Fig. 4 is a vertical longitudinal section of the lower portion of a crate showing a somewhat modified construction of the load-bearing strips.

A represents the opposed end walls and B the opposed side walls of a crate, the interior space of which is subdivided by longitudinal partitions and transverse partitions D to provide pockets for the reception of bottles. To support bottles introduced into the pockets thus provided, the crate is constructed with load bearing strips of flat metal E extended across the bottom thereof, preferably longitudinally of the crate, and with their ends anchored at E' in the end walls A of the crate, and in a plane sufficiently above the bottom plane of the crate to prevent bottles supported on said strips from coming into contact with the ground or other hard object upon which the crate may be resting. Strips E are made of relatively thin flat metal and have their flat faces of lesser transverse dimension presented in the direc-

tion of loading so that their inherent flexibility and resiliency (if made of a resilient metal) will come into play in a manner to absorb the shock of bottles dropping thereon, and safeguard the bottles against breakage.

The load-bearing strips E are preferably arranged in pairs beneath each line of pockets. In order to insure proper spacing of 10 the strips intermediately of their anchored ends, and to sustain them intermediately, a bridging strip F is extended between the other pair of opposed walls, for instance, the side walls B of the crate, and has its 15 ends F' firmly anchored therein, as, for instance, through the medium of vertical rods B'; and this bridging strip has formed through it, in alignment with the load-bearing strips E, slots or apertures F² 20 forming substantially to the transverse section of the load-bearing strips, and the latter are threaded through said slots and confined therein against upward or downward movement as well as lateral displacement 25 or alteration of their spacing. But the strips do not fit in these slots with sufficient tightness to prevent free rocking of the load-bearing strip under its flexing action and consequent transmission of this flexing action 30 from the portion on one side of the bridge to the portion lying on the other side thereof, and thereby increasing the cushioning effect developed by the bottom structure. The ends F' of the bridge F are preferably deflected to a plane 90° from the plane of the main body of the bridge F, thereby not only facilitating the anchoring 35 of the bridge but developing some additional measure of resiliency in the direction 40 of the load.

If preferred, the load-bearing strips may be developed with serpentine deflections or corrugations, as shown at F^x in Fig. 4, to increase their vertical resiliency and to permit 45 them to be introduced between the opposed end walls A with inherent longitudinal strains of tension, but without interfering with the supporting spacing and fulcruming bearing developed by the bridge F 50 at their intermediate points.

I claim:

1. In a bottle crate composed of pairs of opposed confining walls and partitions subdividing its inner space into compartments, a bottom structure providing bottoms for the respective compartments and comprising flexible flat metal load-bearing strips extending between and anchored to the opposed walls of one pair, with their lesser transverse dimension and flat faces presented in the direction of loading, and an intermediate sustaining bridge comprising a flat metal strip extending between and anchored to the opposed walls of the other pair, with its greater transverse dimension 55 presented parallel to the direction of loading and having therethrough, in line with and substantially conforming to the section of the load-bearing strips, slots that maintain the spacing of said load-bearing strips 60 and sustain them intermediately of their anchored ends, with freedom of rocking in the slots.

2. In a bottle crate composed of pairs of opposed confining walls and partitions subdividing its inner space into compartments, a bottom structure providing bottoms for the respective compartments and comprising flexible flat metal load-bearing strips extending between and anchored to the opposed walls of one pair, with their lesser transverse dimension and flat faces presented in the direction of loading, and an intermediate sustaining bridge comprising a flat metal strip extending between and anchored to the opposed walls of the other pair, with its greater transverse dimension 65 presented parallel to the direction of loading and having therethrough, in line with and substantially conforming to the section of the load-bearing strips, slots that maintain the spacing of said load-bearing strips 70 and sustain them intermediately of their anchored ends, with freedom of rocking in the slots.

2. In a bottle crate composed of pairs of opposed confining walls and partitions subdividing its inner space into compartments, a bottom structure providing bottoms for the respective compartments and comprising flexible flat metal load-bearing strips extending between and anchored to the opposed walls of one pair, with their lesser transverse dimension and flat faces presented in the direction of loading, and an intermediate sustaining bridge comprising a flat metal strip extending between and anchored to the opposed walls of the other pair, with its greater transverse dimension 75 presented parallel to the direction of loading and having therethrough, in line with and substantially conforming to the section of the load-bearing strips, slots that maintain the spacing of said load-bearing strips 80 and sustain them intermediately of their anchored ends, with freedom of rocking in the slots.

Signed at Chicago, Illinois, this 25th day of January, 1921.

LEE H. PAYNE.
